UNITED STATES PATENT OFFICE.

LESSING L. KOLE AND EUGENE LOEFFLER, OF MILWAUKEE, WISCONSIN.

VANITY CASE.

Application filed October 27, 1925. Serial No. 65,184.

The object of our invention is to provide novel types of vanity cases having a novel hinged member, which may be either a lid for automatically operating a sifting plate whereby to supply a small quantity of face powder to an accessible portion of the case when the hinged member is raised. It is also an object of our invention to provide a case of this type which is compact and which will not allow the powder to sift through except when it is desired.

We attain these and other objects of our invention by the device illustrated in the accompanying drawings, in which—

15 Figure 1 is a top plan view of our case with the lid open;

Fig. 2 is a section through the case when the lid is closed;

20 Fig. 3 is a section through the case when the lid is open;

Fig. 4 is a horizontal section on line 4—4 of Fig. 2;

25 Fig. 5 is a top plan view of a modified form of our invention having the lid which utilizes a concealed spring;

Fig. 6 is a section through the modified form of our device when the lid is closed;

Fig. 7 is a section through the modified form of our case when the lid is open;

30 Fig. 8 is a horizontal section on line 8—8 of Fig. 6;

Fig. 9 is a top plan view of an improved and preferred form of our invention in which the hinged member consists of a mirror instead of a lid;

Fig. 10 is a section through the case of the type shown in Fig. 9 when the mirror and lid are both closed;

40 Fig. 11 is a section through the case of the type shown in Fig. 9 when the lid and mirror are both open; and

Fig. 12 is a horizontal section on line 12—12 of Fig. 10.

Like numerals designate like parts in 45 each of the several views.

Referring particularly to Figs. 1 to 4 of the drawings, we provide a case 1, having a detachable bottom 2, within which is contained a suitable spring 18 which presses 50 upwardly against a plate 17, on which is placed the face powder 19. The body of the case 1 is provided with an annular flange 6, for engaging the perforated top 7, which has perforations 8 for the powder to sift

through. We provide a movable plate 12, 55 provided with perforations 13, as shown in Fig. 2, said perforations preferably being provided with partial flanged edge portions 14, such as shown in Fig. 4. Plate 12 is provided with a tongue 15, hinged at 16 to the 60 lid 3, which lid is hinged at 4 to the body of the case 1, as shown in Figs. 2 and 3. We provide a suitable mirror 5 on the inside of the lid 3, as shown in Fig. 1. We may provide a rouge cake 23 in the lid 3 65 as illustrated in Fig. 1, or we may provide a mirror only as illustrated in Figs. 2 and 3.

The operation of the device is as follows: The removable bottom 2 is unscrewed from the case 1, and a suitable supply of powder 70 19 is placed on the plate 17, and the bottom is then screwed back in place, the spring 18 tending to press the plate 17 and the powder upwardly. When the lid 3 is opened, the movable plate 12 is pulled along, thus causing the openings 13 in plate 12, and the openings 6 in top 7, to come into communication, momentarily allowing a small amount of powder to sift through to the face of the case top 7, where it is accessible for use. At 75 the same time, the mirror 5 and lid 3 are in position for convenient use, as the tongue 15 of plate 12, which is hinged to the lid 3 at 16, also functions to limit the extent to which lid 3 may be opened.

It is within the contemplation of our invention to modify the arrangement or positioning of the mirror in the case, or to provide a modified type of detachable bottom, or a modified type of spring. We believe 90 the automatic sifting of the powder to be broadly new.

Referring to the modified form of our invention illustrated in Figs. 5 to 8 inclusive, the construction of this case is substantially the same as that illustrated in Figs. 1—4 except as to the following details: We omit the hinged connection 16 of tongue 15 95 on lid 3 and instead provide a stud 20 on lid 3 against which the edge 21 of tongue 15 presses. This pressure is maintained by reason of the provision of a small spring 21 affixed to the outer edge of plate 12, as shown in Figs. 7 and 8.

The tension of this spring against plate 100 105 8 causes it to press the edge 21 of tongue 15 against the stud 20 of lid 3 thereby causing the lid to fly open whenever it is unclasped.

from the conventional snap clasp which holds the lid in locked or closed position. The opening of the lid automatically allows the plate 12 to move relative to perforated 5 top 7 and sift powder therewith to a position accessible to the user.

Referring to the preferred form of our invention illustrated in Figs. 9 to 12 inclusive, we provide in perforated plate 12 a series 10 of apertures 24 engageable by the teeth of a star wheel segment 25 which is swingably mounted on a small stud shaft 26 mounted in a bracket 27 affixed to the perforated top 7. Affixed to star wheel segment 25 is a swing- 15 able member 28 which may be either in the form of a mirror, the lid 3 carrying a small cake of rouge, as illustrated in Fig. 9, or the arrangement may be reversed and the swingable cover member 28 may carry a rouge cake 20 while the lid 3 carries a full mirror 5, as illustrated in Figs. 10 and 11. It is within the contemplation of our invention to make this member a plain plate or a rouge carrying plate 29^a, as shown in Figs. 10 and 11, 25 instead of a mirror 28 as shown in Fig. 10, while retaining its function as an operating member for the sifting plate 12. In consequence of this combination of elements it is 30 possible to raise the lid 3 when sifting in powder.

In the following claims the expression "cover member" shall be construed as applicable to both the lid 3 as shown in Figs. 1-8 or to the cover members 28 and 29 or any 35 similarly operating swingable plate or like element, as illustrated in Fig. 9 or member 29^a as illustrated in Figs. 10 and 11.

It is of course contemplated that the mechanical details of the device will be perfected 40 so that powder cannot escape only when desired except by the operation of the device in the manner hereinabove described.

What we claim is:

1. The combination of a vanity case having 45 a perforated top, a perforated plate slidably mounted beneath the top, and adapted to force powder through the perforations in the top, a cover member hinged- 50 ly mounted on the case, and means pivotally connecting the perforated slideable plate to the cover member.

2. In a vanity case, the combination of a case, a bottom removably mounted on the case, a plate for carrying powder movably 55 mounted within the case, a spring pressing the plate toward the top of the case, a perforated top through which powder may sift, a perforated slideable plate mounted immediately beneath the perforated top, a 60 cover member hingedly mounted on the case, and means operatively connecting the slideable plate with the cover member to operate the slideable plate whenever the cover member is opened, the perforations in the 65 cover member and perforated top being ar-

ranged to register with each other and permit face powder to sift through when the cover member is opened.

3. In a vanity case, the combination of a case, a cover member having an annular 70 inturned flange, a perforated top having its edge portions engaging said flange, a perforated plate slidably mounted beneath the perforated top, the perforations of the top and plate being arranged to register momentarily when the cover member is opened, and means operatively connecting the perforated plate with the cover member of the case, whereby the said plate will be operated when the lid is opened. 80

4. In a vanity case, the combination of a case body, a detachable back in releasable engagement with the body of the case, a plate movably mounted in the case, resilient means tending to press the plate toward the 85 top of the case, a perforated top, a perforated plate slidably mounted beneath the perforated top, a cover member to which the perforated plate is attached and by which it is operated when the cover mem- 90 ber is opened, and a mirror mounted on the lid. 95

5. In combination with the device described in claim 1, the slideable plate having flanged edge portions partially encircling the perforations on the bottom of the plate. 95

6. The combination of a vanity case, a perforated plate, a member holding the perforated plate on the case in position over the powder, a swingable cover member, means operatively connecting the swingable cover member with the perforated plate whereby the opening of said cover member will also operate the plate to sift powder therethrough, and a lid hingedly mounted on the case and operating independently of the lower cover member connected to the slideable plate. 100 105

7. The combination of a vanity case, a perforated plate, a member holding the perforated plate on the case in position over the powder, a swingable cover member, means operatively connecting the swingable cover member with the perforated plate whereby the opening of said cover member will also operate the plate to sift powder therethrough, and a lid hingedly mounted on the case and operating independently of the cover member connected to the slideable plate, one of the aforesaid members carrying a rouge pad and the other of the aforesaid 110 115 cover members carrying a mirror. 120

8. The combination of a vanity case, a perforated plate slidably mounted over the portion of the case containing the powder, a perforated top under which the slideable 125 plate is operatively mounted, a star segment swingably mounted on the top, a cover member affixed to the star segment, and the teeth of said star segment operatively engaging perforations in the perforated plate. 130

9. In combination with the device described in claim 8, a lid or outer cover member mounted on the case and operating independently of the first mentioned cover member.

10. In combination with the device described in claim 8, an outer cover member hingedly mounted on the vanity case, a rouge pad, and a mirror, the rouge pad being affixed to one of the aforesaid cover members and the mirror being affixed to the other of the aforesaid cover members.

11. A vanity case including a body having a powder compartment, in combination with a perforated powder plate carried by the body and reciprocably shiftable relatively to the compartment, a cover member hinged to the body for pivotal movement, an extension upon the plate having hinged connection with the cover member, whereby the plate is automatically shifted on hinged movement of the cover member, and a yield-

ing member for pressing the contained powder in said compartment towards said plate.

12. A vanity case including a body having a base wall and an open end powder compartment, in combination with a perforated plate carried by the body and reciprocably shiftable relatively to the compartment, a cover member hinged to the body for pivotal movement, an extension upon the plate having hinged connection with the cover member, whereby the plate is automatically shifted on hinged movement of the cover member, a bottom plate disposed for movement, and providing a support for the powder contained, within the compartment, and a spring interposed between said bottom plate and base wall for yieldingly supporting the bottom wall within the compartment.
